DOOR

William M. Brunst, Columbus, Ohio, assignor to
 General Door Company, Reno, Nev., a corpora-
 tion of Nevada

Application December 3, 1934, Serial No. 755,709

15 Claims. (Cl. 20—19)

This invention relates to improvements in doors, and particularly to improvements in means for operating a one-piece panel door.

It is an object of this invention to provide a 5 one-piece door with a lever mechanism for moving the door, whereby it may have two movements, one longitudinally and the other a swinging movement.

It is an object of the invention to provide for 10 a doorway a door, which in its vertical position will close the doorway, and in its horizontal elevated position will project through the doorway to form an overhanging canopy protection.

It is also an object to provide a swinging door 15 with means for supporting the door so that it may travel bodily as well as swing, the bodily movement being guided by guides.

It is a further object to provide a one-piece panel door with guides for receiving rollers located on the upper end of the door, said guides being provided with horizontal channels for guiding the upper end of the door horizontally, and with vertical downward extensions, whereby the door may be moved vertically downwardly as it 25 reaches its closing position, the parts of the guides forming the downward extensions serving to hold the upper end of the door against the door jambs.

These and other objects and advantages will appear from the following description taken in 30 connection with the drawings.

Referring to the drawings:

Figure 1 is an inside elevation of one side of the door and the door jamb to which the door is attached, the door and the jamb shown broken 35 away.

Figure 2 is a section on the line 2—2 of Figure 1. In this figure the door is in its closed position.

Figure 3 is a view similar to Figure 2 but with the door elevated, due to the inward opening 40 movement.

Figure 4 is a view similar to Figures 2 and 3 but with the door in a position intermediate that shown in Figure 3 and its open horizontal position.

Figure 5 is a section through the door showing 45 it in its open position.

Figure 6 is a top plan view of the door and its operating mechanism, showing the adjacent wall structure in section.

Figure 7 is a section on the line 7—7 of Figure 1.

Figure 8 is a section on the line 8—8 of Figure 1.

The door of this invention is adapted to be used 55 in connection with garages, storage-rooms and

the like, in which there is an opening or passageway provided on each side with a door jamb 1, and across the top with a lintel 2. Beneath the lintel and extending toward the inside of the building is a strip 3 suitably attached to the lintel in any suitable manner. For the purpose of closing the passageway between the two door jambs a one-piece door 4 is provided.

Each door jamb has thereon an inwardly extending bracket 5 to which a link 6 is pivoted intermediate its ends. To one end of this link 6 one end of a lever 7 is suitably pivoted, while the other end of the lever 7 is pivotally attached to a bracket 8 attached to the door below its middle point. To the other end of the link 6 is pivoted a lever 9 intermediate its ends. One end of this lever 9 is pivotally connected to one end of a link 10, which has its other end pivotally connected to the lever 7 intermediate its ends. The other end of the lever 9 is provided with a counterweight 11.

When the door is in its closed position it engages at each inside edge with a plate or weather strip 12, attached to the jambs of the door. These strips extend from the bottom of the doorway upward to a point past the center line. Cooperating with the weather strips 12 are plates 13 attached to the door and adapted to engage the jambs above the strips 12.

The door is provided at its upper end, at each edge, with a bracket 14, on which there is mounted a roller 15. On the upper edge of the door is a strip 16, which is adapted to engage the inside edge of the lintel 2 and the top edge of the strip 3 when the door is in a closed position, as shown in Figures 1 and 2. The rollers 15 are adapted to travel in horizontal guides 17 in the form of channel tracks. Each guide is supported at its inner end by means of a bracket 18, suitably attached to some part of the building. The ends of the guides adjacent the doorway are supported by means of brackets 19. These brackets have horizontal passageways or horizontal channels 20, corresponding in shape to and in alignment with the channel parts of the trackways or guides 17, and downwardly extending channelways 21 into which the door rollers enter just before the door reaches its closed position.

In the final closing of the door the door moves downwardly, with the rollers in the downwardly extending channelways 21 so that when the door is closed the brackets 19 serve to prevent the inward movement of the upper end of the door. The lower end of the door is held against inward movement by means of the plates 12. The door 55

is prevented from moving outwardly by means of the plates 13 engaging the jambs, and by means of the rollers 15 engaging the lower parts of the brackets 18.

Operation

When it is desired to open the door it is first moved upwardly from the position shown in Figure 2 to that shown in Figure 3. During this part of the operation of the door the rollers move upwardly in the channelways 21 until the rollers reach a position for movement in the channels of the guides 17. This upward movement of the door is aided by the counterweight 16, which acts in a plane parallel to the door for raising the door.

During this upward movement of the door the link 6 serves as a lever, the counterweight acting on one end of the lever to move the door connected to the other end of the lever. The initial upward movement may be brought about by applying downward pressure to the counterweight or by lifting the door. When the door gets in the position shown in Figure 3 a movement of the counterweight to the right or a movement of the lower end of the door to the left causes the whole door mechanism and its operating lever system to move about the pivot of the link 6. In this movement the rollers travel along the guides 17.

Figure 4 shows the door in what might be called the second stage of its opening movement. A continued movement of the counterweight to the right and downward, with the lower end of the door moving to the left and upward will bring the door to its open position, as shown in Figure 5. In this position the door is horizontally disposed, with its lower end projecting out through the doorway to provide a canopy structure. The amount of this projection depends upon the position of the bracket 8 with regard to its distance from the lower end of the door. With this bracket closer to the lower end of the door the door projects a lesser distance through the doorway. With this bracket near the center of the door the projection is greater.

The lever and counterweight mechanism may be attached to one or both sides of the door. If such mechanism is attached to one side of the door a heavier counterweight would be necessary, whereas if attached to both sides of the door a lighter counterweight would be sufficient.

By providing means for lifting the door bodily it is possible to lift it above any collection of ice, snow or other material before swinging it transversely of the door opening. By providing a counterweight that will first move the door vertically in conjunction with the guide and then move it transversely of the door opening, it is possible to utilize a single weight for the compound movement of first lifting the door and then moving it into a horizontal position over the door opening.

It will be understood that I desire to comprehend within my invention such modifications as come within the scope of my claims and my invention.

Having thus fully described my invention, what I claim as new and desire to secure by Letters Patent, is:

1. In combination with structures forming a passageway, guides on said structures defining a continuous path having a relatively short straight vertical portion and substantially longer straight horizontal portion, a single panel door having

rollers in engagement with the guides, and a lever mechanism pivoted to the structures and to the door to lift the door vertically a short distance and then swing the door and cause it to move along the guides.

2. In combination with structures forming a passageway, guides on said structures defining a continuous path having a short vertical extent and a substantially longer horizontal extent, a single panel door having rollers in engagement with the guides, and a lever mechanism pivoted to the structures and to the door to cause it to move vertically a short distance and then horizontally along the guides, said lever mechanism having elements operable to move the door vertically a short distance and other elements operable to swing the door following the initial vertical movement.

3. In combination with structures forming a passageway, guides on said structures, a door having rollers in engagement with the guides, and a lever mechanism pivoted to the structures and to the door to swing the door and cause it to move along the guides, said lever mechanism comprising an arm pivoted intermediate its ends on said structure, a link pivoted at one end to one end of the arm and at its other end to the door, and a lever pivoted to the other end of the arm and having a loose connection at one end with the link.

4. In combination with structures forming a doorway, guides on said structures defining a continuous path having a relatively short straight vertical portion and a substantially longer straight horizontal portion, a single panel door having rollers engaging the guides, and a lever mechanism pivotally supported by said structures and having one end pivoted to the door and having on its other end a counterweight, said lever mechanism being adapted to move the door vertically a short distance and then swing it and comprising a pair of levers and a pair of links pivotally connecting the levers.

5. In combination with structures forming a doorway, guides on said structures defining a continuous path having a relatively short straight vertical portion and a substantially longer straight horizontal portion, a unitary door having rollers engaging the guides, and a lever mechanism pivotally supported by said structures and having one end pivoted to the door and having on its other end a counterweight, said lever mechanism comprising a pair of levers and a pair of links pivotally connecting the levers, one of said links serving as a support for said lever mechanism.

6. In combination with structures forming a doorway, guides on said structures, a single panel door having rollers engaging the guides, and a lever mechanism pivotally supported by said structures and having one end pivoted to the door and having on its other end a counterweight, said lever mechanism having elements operable by the counterweight to move the door vertically and other elements operable by the counterweight to swing the door.

7. In combination with structures forming a doorway, guides extending horizontally from the structures at the top of the doorway, a door for closing the doorway, rollers on the door engaging the guides, a bracket on said structures, a link pivoted intermediate its ends on the bracket, a lever pivoted at one end to one end of the link and pivoted at its other end to the door, a second

- lever pivoted intermediate its ends to the other end of the link, a link pivoted at one end to one end of the second lever and at its other end to the first-named lever intermediate its ends, and 5 a counterweight on the other end of the second lever.
8. In combination with a building having a door opening, a door for closing said opening, a counterweight, a guide, and means connecting 10 said counterweight to the door, whereby the movement of the counterweight first elevates the door vertically and then moves the door vertically and horizontally until the door assumes a position in substantially a horizontal plane above the door 15 opening.
9. In combination with a building having a door opening, a door for closing said opening, a counterweight, a guide, means connecting said counterweight to the door, whereby the movement of 20 the counterweight first elevates the door vertically and then moves the door vertically and horizontally until the door assumes a position in substantially a horizontal plane above the door opening, and means for stopping said door in its 25 horizontal movement so that it will project partly through the door opening to form a canopy over the door opening.
10. In combination with a building having a door opening, a one-piece door, means to guide 30 said door vertically, means to elevate the door vertically a relatively short distance of the door's travel, and means to guide the upper end of the door horizontally a relatively long distance of the door's travel, said guide means being attached 35 opposite one another to the respective door jambs and comprising a pair of unitary brackets in the form of an inverted L, defining a closed path for cooperation with follower means disposed on the side edges of the door.
- 40 11. In combination with a building having a door opening, a one-piece door, means to guide said door vertically, means to elevate the door vertically a relatively short distance of the door's travel, means to guide the upper end of the door 45 horizontally a relatively long distance of the door's travel, and a counterweight articulated to the door and to the building so arranged as to first lift the door vertically and then continue to move it into a horizontal position.
- 50 12. In combination with a building having a door opening, a door closure, tracks mounted adjacent the top of the door closure, said tracks being arranged on either side of the door and comprising a relatively short vertical portion and 55 a relatively long horizontal portion, rollers on the upper edges of said door traveling respectively in said tracks, a counterweight, and means for connecting said counterweight to the building and the door, whereby the counterweight first moves
- the door and its rollers vertically on the tracks and then moves the door and its rollers horizontally, the rollers traveling in the horizontal portions of the tracks.
13. In combination, a structure having a door opening, a stationary flange adjacent each side of the door opening extending part way up the sides of the door opening and overlapping the door opening, a door overlapped by said flange, similar flanges carried on the edges of said door overlapping the door jamb, tracks comprising vertical and horizontal portions adjacent the top of the door opening on either side thereof, rollers at the top of the door traveling in said tracks, a counterweight, and means of articulately connecting said counterweight to the door and to the structure adjacent the door opening, whereby the door is first moved vertically and thence into a horizontal position adjacent the top of the door opening.
14. In combination, a structure having a door opening, a stationary flange adjacent each side of the door opening extending part way up the sides of the door opening and overlapping the door opening, a door overlapped by said flange, similar flanges carried on the edges of said door overlapping the door jamb, tracks comprising vertical and horizontal portions adjacent the top of the door opening on either side thereof, rollers at the top of the door traveling in said tracks, a counterweight, means of articulately connecting said counterweight to the door and to the structure adjacent the door opening, whereby the door is first moved vertically and thence into a horizontal position adjacent the top of the door opening, and door jamb means over the top of the door opening adapted to engage with the top of the door.
15. In combination, a structure having a door opening, a stationary flange adjacent each side of the door opening extending part way up the sides of the door opening and overlapping the door opening, a door overlapped by said flange, similar flanges carried on the edges of said door overlapping the door jamb, tracks comprising vertical and horizontal portions adjacent the top of the door opening on either side thereof, rollers at the top of the door traveling in said tracks, a counterweight, means of articulately connecting said counterweight to the door and to the structure adjacent the door opening, whereby the door is first moved vertically and thence into a horizontal position adjacent the top of the door opening.
